UNITED STATES PATENT OFFICE.

JAMES POWERS, OF NEW YORK, N. Y.

TRENCH DIGGER.

Application filed August 18, 1921. Serial No. 493,276.

To all whom it may concern:

Be it known that I, JAMES POWERS, a citizen of the United States, residing in New York, in the county of New York and State of New York, have invented certain new and useful Improvements in Trench Diggers, of which the following is a specification.

This invention relates to machines or apparatus for digging trenches and has for one object to improve generally the simplicity and efficiency of such machines and to provide in a device or apparatus of this kind very efficient means for cutting the trench and separate means for removing the material cut by the cutting means.

Other objects of the invention will appear as the description proceeds, and while herein details of the invention are described, the invention is not limited to these, since many and various changes may be made without departing from the scope of the invention as claimed.

In the accompanying drawing, showing by way of example one of many possible embodiments of the invention.

Fig. 1 is a side elevation of the machine in operative position.

Fig. 2 is a plan of the machine;

Fig. 3 is a fragmental rear end elevation partly in section;

Fig. 4 is a fragmental side elevation partly in section taken on the line 4—4 of Fig. 3;

Fig. 5 is a plan of one of the milling cutter supports of the machine drawn to a larger scale;

Fig. 6 is a central sectional view of the support, taken on the line 6—6 of Fig. 5 and drawn to a still larger scale;

Fig. 7 shows a face view and axial section of one of the cutters;

Fig. 8 is a face view of another form of cutter; and

Fig. 9 is a diagrammatic view showing the discharge opening of the chute.

The operating parts of my trench digger are mounted on a main frame comprising forward and rear cross pieces 10 and 11 (Fig. 2) and side members 12 and 13. Said frame carries at its front end a vertical steering post-sleeve 15 (Fig. 1) in which is a rotatable steering post 16 provided at its lower end with a castor fork 17 carrying a steering road wheel 18. A bevel gear 20 on the upper end of said post meshes

with another gear 21 carried on the forward end of a shaft 22 mounted in a bracket 23 and carrying the hand wheel 24 at its rear end.

Axle brackets 27 (Fig. 3) secured to the rear of said side members 12 and 13 respectively carry out-turned shafts 28 carrying the drive road wheels 30 rotatably mounted on said shafts and provided at 65 the inner end of their hubs with sprocket wheels 31.

An internal combustion motor 33 (Figs. 1 and 2) or other engine is mounted on a plate 34 carried on the forward part of 70 said side members 12 and 13 and is provided with a bevel gear 35 on the rear part of its drive shaft. A U-shaped transmission housing 37 (Fig. 3) having an upper yoke and having the lower ends of its sides or 75 arms 38 outwardly turned and mounted on said side members, is provided at the mid portion of its sides with bearing openings 39 carrying bearing bushings 40 receiving a transverse main drive shaft 41 carrying drive sprockets 42 at its outer ends with which are engaged chains 44 between said drive sprockets 42 and the sprockets 31 of said road wheels.

A counter shaft 45 (Fig. 2) transversely mounted forward of said housing is provided with a bevel gear 46 engaging said bevel gear 35 of the motor shaft. A clutch member 47 loose on said counter shaft meshes with a slid able member 48 splined 80 on said counter shaft and provided with an annular groove 49 in which engages the lower end of a lever 50 (Fig. 1) fulcrumed on a bracket 51 on the forward part of the housing 37 and having its upper end received in the bifurcated forward end of a hand lever 52 fulcrumed on the bracket 53 for operating the clutch. A sprocket connection is provided comprising a sprocket chain 55 (Fig. 2) and a sprocket wheel 56 100 and sprocket teeth on the member 47 whereby said main drive shaft is driven from said counter shaft when said clutch is closed.

A milling shaft carrier 60 (Figs. 1 and 4) is provided with upper extensions 61 pivotally received on said bushing 40 and provided at its lower end with a worm housing 62 disposed near the ground when the carrier is in vertical position. Said worm housing carries a milling shaft 63 rotatably mounted in and projecting downwardly therefrom co-axial with said carrier. A

worm wheel 64 in said worm housing and on said milling shaft is engaged by a transversely disposed worm 65 mounted on a worm shaft 66 having one end projecting at 5 one side of said worm housing. A sprocket connection between said worm shaft 66 (Fig. 3) and said main drive shaft comprises sprocket wheels 68 and 69 and a sprocket chain 70 disposed outside of said transmission housing 37.

A plurality of spider-members 72 (Figs. 1 and 5) having central hubs 73 fast on said milling shaft 63 are provided with radial milling arms 74 provided at their outer ends 15 with milling cutters 75 secured thereto by bolts 76 and held against rotation by pins 78 (Fig. 6). These cutters may be round (Fig. 7) or triangular as the cutter 75' (Fig. 8) or any other desired shape.

20 A worm casing 79 (Fig. 1) mounted on a rear bracket 80 fast on the rear part of said transmission housing 37 guides the upper part of a sector rack 81 pivotally connected at its lower end to said worm housing 62 and 25 having its upper end toothed and engaged by a worm 82 carried on a worm post 83 vertically mounted in said worm casing and carrying an operating hand-wheel 84 at its upper end for raising said milling shaft and 30 cutters to the position of Fig. 4.

A conveyor trough 85 having a transversely disposed drum pulley 86 (Fig. 1) rotatably mounted at its lower end and a similar pulley on and driven by a transversely mounted operating shaft 87 at an intermediate part of the trough is in part supported by supporting links 88 (Fig. 4) pivotally mounted on a boss 89 (Fig. 3) so as to be radial to said transmission shaft. The outer 35 end of the links is pivotally received on said operating shaft 87. An adjusting link 90 (Fig. 1) pivotally connecting a lateral bracket 91 (Fig. 3) on the lower part of said trough to a clamp carrying bracket 92 mounted on one of said side members 12 is held in adjusted position by a clamping bolt 93 passed through said bolt carrying bracket 45 and a slot 94 (Fig. 1) in said link.

A sprocket connection between said transmission shaft 41 and said operating shaft 87 and comprising sprocket wheels 96 and a sprocket chain 97 is provided for driving the operating shaft. A conveyor comprising band 98 disposed over said pulley drums 86 55 and provided with excavating blades 99 for drawing material from said milling cutters to the upper part of said trough, discharges the material into a laterally projected hopper 100, (Fig. 9) secured under an opening 60 101 (Fig. 1) near the upper part of said trough, for discharging material to one side of the ditch.

A driver's seat 102 mounted on the rear of said frame is in convenient position to said 65 lever 52 and hand-wheels 24 and 84.

The operation of the machine is very simple. The machine being ready to operate, with the milling cutters and trough raised to the position of Fig. 4, the clutch may be thrown in and the machine guided to the location where it is intended to commence digging the trench. The milling cutters are then lowered to the ground by operating the hand-wheel 84 until the cutters take the position of Fig. 1. At the same time the trough 85 is lowered also to the position of Fig. 1, whereupon the forward movement of the machine causes the cutters 75 to cut away the forward end of the excavation thereby loosening the soil and throwing it back to the blades 99 which drag the loosened material back into the trough and up to the opening 101 and discharge it into the hopper 100 which in turn laterally discharges the material as shown in Fig. 9, either depositing it at the side of the trench or into a suitable conveyance drawn along at the rear of the machine.

When the trough 85 is to be lowered, the handle 103 (Fig. 3) is rotated to loosen the 90 hold of the clamping nut upon the link 90, thereby permitting the trough to be lowered. When the right position of the trough is attained, rotation of the handle 103 clamps said link in place, thereby positioning the 95 trough.

When the cutters 75 or 75' become worn at one edge portion, they may be adjusted to bring other edge portions into play by removing the bolt 76 and the cutter, rotating the cutter a bit and replacing it on the 100 arm 74.

In general it may be stated that the purpose of this machine is to provide a mechanism which will cut, dig, excavate or otherwise make a trench, more expeditiously, accurately and at a less expense both in the power necessary to operate the mechanism, the other expenses incident to the operation of such a machine and in the labor and attention required. This machine can be used also for ditching, dredging, grading, leveling, tilling, sub-soil plowing and in numerous other classes of excavating, cutting and filling work generally.

115 In many uses, particularly when the machine is used as a sub-soiler or other cultivation, the conveyor may be omitted or held out of use. Under other circumstances it may sometimes be desirable to omit or remove the milling mechanism and use the conveyor alone.

I claim as my invention:

1. In combination, a main frame; steering and drive road wheels therefor; a motor thereon; a transverse main shaft mounted on said frame and having operative connection with the drive road wheels and motor; a downwardly disposed milling shaft carrier pivoted radial to said main shaft; 125

1. a milling shaft carried by the carrier alined therewith and rotated by said main shaft; milling arms provided with end milling cutters carried on the milling shaft; means for raising and lowering the carrier; a conveyor trough provided with a conveyor means and an upper lateral discharge chute, and an intermediate transverse operating shaft operatively connected to the conveyor means; supporting links having their ends pivoted radial to said main and operating shafts; an adjustable link pivotedly connected to said main frame and trough; and means for clamping the link in adjusted position.
2. In combination, a main frame having side members; steering and drive road wheels therefor; a motor thereon; a transverse main shaft mounted on said frame and having operative connection with the motor; a U-shaped transmission housing having an upper yoke and having the lower ends of its arms mounted on said side members, the mid portion of the sides of the housing being provided with alined bearing openings surrounded by inner bosses; bearing bushings in said bearing openings and receiving the transverse main shaft; a chain and sprocket connection between the outer ends of said main shaft and said road wheels; a carrier pivoted radial to said drive shaft; a milling shaft on said carrier driven by said drive shaft, and carrying cutters; a conveyor behind said cutters and driven by said main shaft; and links pivotally connecting said conveyor to said main shaft and frame.
3. In combination, a movable frame; a transverse drive shaft thereon; a milling shaft carrier having its upper part radial to said drive shaft and provided at its lower end with a worm housing extending to near the ground when the carrier is in vertical position; a milling shaft mounted in and projecting downwardly from said worm housing co-axial with said carrier; a worm wheel in said worm housing on said milling shaft; a transversely disposed worm shaft mounted in said housing and carrying a worm engaging said worm wheel and having one end projecting at one side of said worm housing parallel with and operatively connected with said main drive shaft; and a plurality of spider-members having central hubs fast on said milling shaft and provided with radial milling arms and provided at their outer ends with milling cutters.
4. In combination, a movable frame; a transmission housing thereon; a transverse main shaft mounted in said housing; a downwardly disposed milling shaft carrier pivoted radial to said main shaft; a worm casing mounted fast to the rear of said transmission housing; a sector rack pivotally connected at its lower end to said carrier and having its upper end toothed and guided in said worm casing; a hand operated worm post vertically mounted in said worm casing and provided with a worm engaging said teeth for raising said milling shaft and cutters; a milling shaft carrier pivoted radial to said drive shaft; and a milling shaft on said carrier driven by said drive shaft and carrying cutters.
5. In combination, a movable frame; a transverse drive shaft thereon; a milling shaft carrier pivoted radial to said drive shaft; a milling shaft on said carrier driven by said drive shaft and carrying cutters; a conveyor trough provided with a conveyor means and an upper lateral discharge chute, and an intermediate transverse operating shaft operatively connected to the conveyor means; supporting links having their inner ends pivoted radial to said main and operating shafts; an adjustable link pivotally connected to said main frame and trough; and means for clamping the link in adjusted position.
6. In combination, a movable frame; a transverse drive shaft thereon; cutters carried by the frame; a conveyor trough provided with a discharge opening in the upper part of its lower face; a transverse discharge chute under said opening; transversely disposed drum pulleys rotatably mounted at the upper and lower parts of said trough; a transverse operating shaft for driving said pulleys; supporting links pivoted at the upper ends radial to said operating shaft, whereby said trough is in part supported by said links; a lateral bracket on the lower part of said trough; a clamp carrying bracket mounted on one of said side members; a clamping bolt passed through said bolt carrying bracket; an adjusting link pivotally connecting said lateral bracket to said clamping bolt; a chain sprocket connection between said drive shaft and said operating shaft; and a band disposed over said pulley drums and provided with excavating blades for drawing material from just behind said milling cutters to the upper part of said trough for discharge through said chute, for discharging material to one side of the trough.
7. In combination, a movable frame comprising side members; a transverse drive shaft thereon; a milling shaft carrier pivoted radial to said drive shaft; a milling shaft on said carrier driven by said drive shaft and carrying cutters; a conveyor behind said cutters and driven by said main shaft and comprising a trough; links pivotally connecting said conveyor to said main shaft and frame; a lateral bracket on the lower part of said trough; a clamp carrying bracket mounted on one of said side members; a clamping bolt passed through said bolt carrying bracket; and an adjustable

- link pivotally connected to said lateral bracket to said clamping bolt and provided at the upper end with a slot receiving the clamping bolt.
5. In combination, a movable frame; a drive shaft mounted on said frame transverse to its path of movement; a downwardly disposed milling shaft carrier radial to said shaft and pivotally connected to said shaft; a milling shaft carried by the carrier alined therewith and rotated by said main shaft; and milling cutters carried on the milling shaft; a sector rack pivoted on the carrier and means cooperating with said rack to adjustably position the carrier.
10. In combination, a movable frame; a drive shaft mounted on said frame transverse to its path of movement; a downwardly disposed milling shaft carrier pivot- 20 ed radial to said shaft; a milling shaft carried by the carrier alined therewith and rotated by said main shaft; milling cutters carried on the milling shaft; and means for adjusting the carrier up and down; a 25 toothed sector pivotally mounted on the carrier and hand operable means cooperat- ing with said sector to adjust the carrier up or down.
15. In combination, a movable frame; a transverse drive shaft thereon, a milling shaft carrier pivoted radial to said drive shaft; a milling shaft on said carrier driven by said drive shaft and radial to the shaft; and a plurality of spider members having 30 central hubs fast on said milling shaft, and provided with radial milling arms having radial vertical faces provided with central bolt holes; a pin projecting from each vertical face; a bolt in the bolt hole; and a 35 milling cutter on said bolt and having its complete periphery formed into a cutting edge and provided with equi-angularly spaced holes receiving said pin to hold the cutter against rotation.
40. In combination, a trench digger, the combination with a downwardly disposed rotary milling shaft, of a plurality of radial carriers fixed to said shaft, cutters adjustably positioned on the periphery of said radial carriers, a rack pivoted to said shaft, and a gear for 45 actuating said rack whereby to relatively displace said shaft in an angular direction.
45. In a trench digger, the combination with a rotary milling shaft, of a spider member having its central hub fast on said milling shaft, said spider member having radial milling arms, radially vertical faces
- provided with central bolt holes on said arms, a pin projecting from each vertical face, a bolt in each bolt hole, and a milling cutter on each bolt and having its complete periphery formed into a cutting edge and provided with a hole to receive one of said pins to hold the cutter against rotation.
50. A trench digger comprising a downwardly disposed rotary milling shaft radially adjustable in the vertical plane of the path of the digger; a plurality of radial 55 arms fast on said milling shaft and provided with radial vertical faces; a clamping bolt perpendicularly disposed in each of said faces; and a flat milling cutter rotatably adjustably secured on said bolt and having its periphery formed into cutting edges.
55. In combination, a movable frame; a rotary milling shaft on said frame; a plurality of spider-members having central 60 hubs fast on said shaft and provided with radial milling arms having radial vertical faces provided with central bolt holes; a pin projecting from each vertical face; a 65 bolt in the bolt hole; and a milling cutter on said bolt and having its complete periphery formed into a cutting edge and provided with equi-angularly spaced holes receiving said pin to hold the cutter against rotation.
60. In a trench digger, the combination with a downwardly disposed rotary milling shaft, of a plurality of radial carriers fixed to said shaft, cutters adjustably positioned on the periphery of said radial carriers, a 65 rack pivoted to said shaft, and a gear for actuating said rack whereby to relatively displace said shaft in an angular direction.
65. In a trench digger, the combination with a downwardly disposed rotary milling shaft, of a plurality of radial carriers fixed to said shaft, cutters adjustably positioned on the periphery of said radial carriers, rack and pinion means for angularly adjusting said shaft, and pivotally mounted conveying means positioned adjacent the milling means for laterally distributing the cut material.
70. JAMES POWERS.
